UNITED STATES PATENT OFFICE.

AUGUSTIN J. CHEVRETTE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-CARRIER SUPPORT FOR WEFT-REPLENISHING LOOMS.

Application filed February 2, 1923. Serial No. 616,461.

To all whom it may concern:

Be it known that I, AUGUSTIN J. CHEVRETTE, a citizen of the United States, residing at Worcester, in the county of Worcester and State of Massachusetts, have invented a new and useful Weft-Carrier Support for Weft-Replenishing Looms, of which the following is a specification.

This invention relates to a weft replenishing loom of the type in which a non-rotary or stationary magazine is used from which a desired weft carrier or bobbin is supplied for transfer upon indication of weft exhaustion in the active shuttle. In such magazines a selected weft carrier is first advanced to transfer position, at which point it must be yieldingly supported for engagement by the actuating device or transference by which it is inserted in the active shuttle, simultaneously with the ejection of the exhausted weft carrier therefrom.

It is the object of my invention to provide an improved support for a weft carrier in transfer position, so engaging the weft carrier that the yarn may be freely withdrawn from the tip end of the weft carrier during transfer and that the possibility of breakage during transfer will be greatly reduced.

In the preferred form, my improved support engages the weft carrier upon the rear side only and at a point substantially spaced from the tip of the weft carrier.

My invention further relates to arrangements and combinations of parts which will be hereinafter described and more particularly pointed out in the appended claims.

A preferred form of the invention is shown in the drawings, in which

Fig. 1 is a front view of parts of a magazine embodying my improvements;

Fig. 2 is a side elevation thereof;

Fig. 3 is a sectional side elevation taken along the line 3—3 in Fig. 4,

Fig. 4 is a sectional plan view taken along the line 4—4 in Fig. 2, and

Fig. 5 is a similar view, showing a slight modification.

Referring to the drawings, I have shown parts of a stationary magazine comprising a stand or frame 10 having a base 10^a by which it is secured in fixed position on the loom and having an outer end frame 11 secured in spaced relation to the stand 10 by a plurality of cross rods 12.

The stand or frame 10 is provided with 55 a plurality of vertically extending ribs 13 (Fig. 3) forming a series of compartments 14 for the butts of the weft carriers or bobbins W. The tips of the bobbins are similarly supported in guideways on the end frame 11 and vertically extending passages 15 therein permit the weft ends to be drawn outward from the weft carriers and to be secured to the end holder 16 (Figs. 1 and 4).

The weft carriers W are held in their respective compartments by supporting devices or cradles, not shown, which are actuated upon indication of weft exhaustion to release and advance a selected weft carrier to the position shown particularly in Figs. 3 60 70 and 4 of the drawings.

In this position, the butt of the weft carrier is engaged on the front side by a fixed guide plate or projection 17 and on the rear side by a yieldingly mounted release device 65 75 18. The tip of the bobbin is engaged on the front side by a member 19 which is also adapted to yield as the bobbin or weft carrier is moved downward. The tip of the bobbin is left free and unsupported at the rear side thereof but the weft carrier is engaged on its rear side at a point intermediate its ends by a rod or arm 20 forming the lower end of a supporting device 21 pivoted at 22 to the end frame 11. This arm 20 also 80 acts as a guide for the weft carrier as the carrier is advanced toward transfer position.

The arm or rod 20 may be adjusted in the sleeve 24 at the lower end of the member 21 both longitudinally of the weft carrier W 90 and also angularly in the sleeve 24. A set screw 26 in the member 21 also engages one of the cross rods 12 and provides for adjustment of the arm 20 toward and from the weft carrier. The point of engagement of 95 the arm 20 with the weft carrier is preferably on the opposite side of the longitudinal center of gravity of the weft carrier from the butt in order that the weft carrier may not be unbalanced when supported by the 100 arm 20 and the release device 18.

As soon as the weft carrier is transferred, its movement with the lay toward the rear commences, so that the weft end is carried directly away from the support 19 on the front side of the tip. The rear side of the weft carrier tip is free from engagement with any supporting device beyond the point

of contact of the support 20, and the weft may thus be freely drawn therefrom without danger of breakage or entanglement.

The general position of the transferrer is indicated at 27 in Fig. 1, but the mechanism for transferring the weft carrier and for indicating and advancing a selected weft carrier to transfer position forms no part of my invention and for a full disclosure thereof, reference is made to the prior patent to E. H. Ryon, No. 1,030,748 issued June 25, 1912.

In Fig. 5, I have shown the weft end holder 16^a positioned rearwardly of the transfer position of the weft carrier W. This rearward displacement is made possible by the clear path of the weft from the tip of the weft carrier to the weft holder and is of material advantage, as it reduces the tension on the weft end caused by rearward movement of the lay and also presents the weft in better position for entering the shuttle eye.

Having thus described my invention and the advantages thereof, I do not wish to be limited to the details herein disclosed otherwise than as set forth in the claims but what I do claim is:—

1. In a weft replenishing loom, a magazine, a transferrer, and means to support a weft carrier in transfer position in said magazine, said means comprising a pair of members supporting the butt of the weft carrier, a member supporting the tip of said weft carrier on its front side only, and a supporting member engaging the rear side of said weft carrier at a point intermediate its ends.

2. In a weft replenishing loom, a magazine, a transferrer, and means to support a weft carrier in transfer position in said magazine, said means comprising a bent arm pivoted to said magazine near the top thereof and substantially vertically over the weft carrier to be transferred, and engaging said weft carrier on its rear side at a point intermediate its ends.

3. In a weft replenishing loom, a magazine, a transferrer, means to support a weft carrier in transfer position by engagement therewith only at points spaced from the rear side of the tip portion thereof, and a

weft end holder offset rearwardly from the transfer position of a weft carrier in said magazine.

55

4. In a weft replenishing loom, a magazine having a plurality of substantially vertical weft carrier compartments, means to support the butt of a weft carrier when the latter is advanced to transfer position, and an additional yielding support for said weft carrier effective to engage the weft carrier when it is released from one of the compartments in the rear portion of said magazine and to guide said weft carrier to transfer position, said additional yielding support engaging the weft carrier at the rear lower side thereof and at a point on the opposite side of the longitudinal center of gravity from the butt substantially spaced from the tip of the weft carrier.

65

5. In a weft replenishing loom, a magazine having a plurality of parallel weft carrier compartments, a support yieldingly mounted and positioned under said compartments to guide a weft carrier from one of said compartments to transfer position, said support yieldingly engaging the rear side of said weft carrier when in transfer position at a point on the opposite side of the longitudinal center of gravity from the butt substantially spaced from the tip portion of the weft carrier from which the weft is unwound.

75

6. In a weft replenishing loom, a magazine having a plurality of substantially parallel weft carrier compartments, and supporting means for the weft carriers effective to receive a weft carrier from a magazine compartment and to guide the same to transfer position, said supporting means comprising a pair of guiding supports for the butt of the weft carrier and additional guiding supports for the weft carrier spaced substantially from the butt thereof, at least one of said last-named supports engaging and guiding the weft carrier at a point approximately mid-way between the butt of the weft carrier and the tip portion thereof from which weft is drawn.

80

100 In testimony whereof I have hereunto affixed my signature.

AUGUSTIN J. CHEVRETTE.
